UNITED STATES PATENT OFFICE.

JEROME B. SECOR, OF DERBY, CONNECTICUT, ASSIGNOR TO THE WILLIAMS TYPEWRITER COMPANY, OF DERBY, CONNECTICUT, A CORPORATION OF IOWA.

TABULATING DEVICE FOR TYPE-WRITING MACHINES.

SPECIFICATION forming part of Letters Patent No. 767,838, dated August 16, 1904.

Application filed March 21, 1902. Renewed April 21, 1904. Serial No. 204,284. (No model.)

To all whom it may concern:

Be it known that I, JEROME B. SECOR, a citizen of the United States, residing at Derby, in the county of New Haven and State of Connecticut, have invented certain new and useful Improvements in Tabulating Devices for Type-Writing Machines, of which the following is a specification.

This invention relates to improvements in tabulating devices for type-writing machines; and its object is to facilitate the tabulating operation by providing column-stop devices which can be instantly set to operate at any given column without necessity of careful adjustment by the operator.

With the usual tabulating devices it is necessary when a column is to be written in a definite part of a page to carefully adjust an adjustable stop to the required point. This requires time and care, and the removal of the stop to one side when tabulation is no longer desired also takes an appreciable time.

My present invention comprises the provision of column-stops that are not adjustable—that is, are not movable longitudinally of the carriage—but may be moved laterally with respect to the carriage to bring them into or out of coöperative relation with the tabulating-key device. Said tabulating-key device may have a single stop-key or a plurality of keys to give a decimal or denominational stop.

In the accompanying drawings, Figure 1 is an end elevation with parts broken away of a type-writing machine, illustrating the invention. Fig. 2 is a partial rear elevation of the same. Fig. 3 is a detail view of a spring-drum provided with a peripheral graduated stop device, as hereinafter described.

1 may represent the frame, and 2 the carriage, of any usual or suitable form of type-writer. The column-stop-controlling devices carried by the carriage consist of shiftable tappet-lugs 4, which in this illustration are shown as pivoted to swing vertically on the carriage-bar 3, so as to be brought into or out of coöperating relation with a cam device 10' on a bell-crank lever 10, pivoted at 10^a to

the machine-frame and engaging at its other end with a lever 11, pivoted at its lower end 50 at 11^a to the machine-frame and having an arm or lug 11', which extends under a series of stop-levers 12, pivoted on a pivot pin or shaft 13. These levers 12 are each formed at its end with a projecting nose, as shown in 55 dotted lines in Fig. 2, extending obliquely downward and adapted to engage with stop means 14, formed on the periphery of the usual spring-drum 15, which is geared to the carriage in the usual manner. The stop means 60 on the spring-drum may, as shown in Fig. 3, consist of oblique slots 14, formed in a band on the outside of said drum and having on their sides which engage with the stop-levers 12 steps 15', arranged at angular distances 65 circumferentially of the spring-drum corresponding with the letter-space feed on the carriage. The distance asunder of the oblique slots 14 circumferentially of the drum determines the distance between columns and corresponds with the distance between the tappet-lugs 4, which may represent one inch, more or less, in the feed movement of the carriage. The steps 15' (here shown nine in number) in each slot 14 correspond with letter-spaces or 70 decimal value of the figures in each column. There is one stop-lever 12 for each of the steps 15', and these stop-levers are severally actuated by separate tabulating-key levers 7, one for each, which bear upwardly against the respective stop-levers 12, either directly, as in the case of the upper three, or through the medium of rods 16, as shown in the second and third sets of three. In Fig. 1 dotted lines indicate the terminal ends of the key-levers 7 75 in each range which are controlled by the one shown, each successive key-lever being made slightly shorter than the one before it, so that each will actuate one of the stop-levers 12. In like manner the stop-levers 12 are made of 80 different lengths, so that each will be engaged by one only of the key-levers. The respective stop-levers 12 are formed on their under sides with notches 12', that allow free downward movement of the lever except when the 85 lever 11 is moved (to the right in Fig. 2) by 90

the bell-crank 10, as aforesaid, when a horizontal lug or arm 11' on said lever 11 comes under a projection or shoulder 12" on all the levers 12 and prevents depression of said levers. Springs 7' serve to return the key-levers 7 to normal position. A release-lever 18 is fulcrumed to the fixed frame at 18" and connected to a cross-bar 18', which extends over all the levers 12, so that when any one of said levers is moved one end of the said release-lever will be raised and the opposite end will bear down on a pin 19, connected with escape mechanism (not shown) to effect the release of the carriage from the escapement or step-by-step feeding mechanism, which may be of usual or well-known form. I prefer to provide means for easing off the shock due to arrest of the spring-drum by the stop-levers 12, and for this purpose I mount the pivot-shaft 13 in a slot-bearing 20' on the fixed frame part in such manner that it can slide parallel to the motion of the carriage, and a spring 21 is provided which draws the said shaft toward the spring-drum.

25 The operation of the device is as follows: Normally all of the stop-controlling devices 4 are in depressed position, as indicated for the device at the left in Fig. 2, so that in the travel of the carriage the stop-controlling devices 4 will successively strike and depress the cam device 10' and through the lever 10 will operate the lever 11 and hold the lug or arm 11' thereon under the shoulder 12" of all the levers 12, thereby preventing operation of any of the stop-levers 12. If the operator desires to write in any particular column, he moves the corresponding column-stop-controlling device 4 to a position wherein it will be free of the cam device 10', and when in the travel 40 of the carriage this column-stop comes opposite the cam device 10' said cam device being free will allow the lever 11 to remain out of coöperative relation with the shoulder 12" on stop-levers 12, thereby leaving the said stop-levers free to be depressed. The lever 11 is restored to normal position by a suitable spring and by its pressure against the lower end of the bell-crank lever 10 restores this to normal position when released. Assuming 45 that the operator has depressed the proper tabulating-key 7 for the denomination he desires to write, the corresponding stop-lever 12 will fall against the spring-drum periphery, and the principal stopping means 14, which 50 is then opposite the stop-levers, will engage with the operated stop-lever 12 by that one of its respective stops which corresponds to said stop-lever. In such engagement the arresting of the carriage is not sudden, but is taken up 55 by the spring 21, the carriage being finally arrested by the shaft 13 reaching the other end of the pivot-slot 20'.

The stop-lugs 4 retain by friction either position in which they are adjusted. The distance to which they may be pulled out into

operative position being limited, they offer unyielding resistance to the stop-key device used in conjunction therewith.

From the above description it will be apparent that the oscillating stop-levers 12, operating in conjunction with the oblique sets of teeth 15' on the feed-drum, constitute rotatable denominational stops which are rotated to bring them to different denominational positions, and the key-levers 7 constitute means for locating said denominational stops at different denominational positions, also that the adjustable dogs 4, bell-crank levers 10, and levers 11, in combination with the stop-levers 12, constitute tabulating-stops coöperating with the denominational stops, for the reason that the manipulation of the several equidistant adjustable dogs 4 locates the column in which the printing is to be done.

The following is what I claim as new and desire to secure by Letters Patent:

1. In a tabulating device for type-writing machines, the combination of tabulating-key mechanism mounted on the frame and a plurality of stop-controlling devices 4 mounted on the carriage at fixed distances apart and movable laterally with respect to the direction of movement of the carriage so as to bring them into or out of coöperative relation with the tabulating-key mechanism on the frame, substantially as described.

2. In a tabulating device for type-writing machines, the combination of tabulating-key mechanism mounted on the frame and a plurality of stop-controlling devices 4 pivoted at fixed distances apart on the carriage and movable laterally with respect to the direction of movement of the carriage so as to bring them into or out of coöperative relation with the tabulating-key mechanism on the frame, substantially as described.

3. In a tabulating device for type-writing machines, the combination of key-controlled stopping mechanism mounted on the frame and a plurality of controlling devices mounted at fixed distances apart on the carriage and independently movable laterally with respect to the movement of the carriage so as to bring them into or out of coöperative relation with the key-controlled stopping mechanism on the frame and thereby determine the operativeness or inoperativeness of the latter, as explained.

4. The combination with the carriage of an operating spring-drum having a column-stop device on its periphery and a series of key-controlled stop devices engaging with the stop device on the drum and arresting its movement at different points determined by the selected key, substantially as described.

5. The combination with the carriage of an operating spring-drum having on its periphery a graduated series of stops at angular distances apart circumferentially of the drum corresponding with determined intervals in

the movement of the carriage, and key-controlled stop mechanism engaging with one or other of said stops so as to arrest the movement of the carriage at variable points, substantially as described.

6. A tabulating device for type-writing machines, comprising key-controlled stopping means and a plurality of controlling devices mounted on the carriage at fixed distances apart and movable laterally with respect to the motion of the carriage to control the action of the key-controlled stopping means.

7. The combination with the carriage of a type-writing machine and its operating spring-drum, of stop devices arranged on said spring-drum at fixed distances apart, controlling devices arranged on the carriage at corresponding fixed distances apart, key-operated stopping means on the spring-drum, and means engaged by the controlling devices on the carriage, and controlling the operation of the key-operated stopping means.

8. A tabulating device for type-writers comprising a part connected with the carriage, stopping means arranged on said part, a stop-lever engaging with said stopping means, and a spring-support for the said lever to take up the shock of arrest of the carriage.

9. The combination with the carriage and its operating spring-drum of column-stop devices on said spring-drum, and a plurality of key-controlled means engaging with said column-stop devices adapted to arrest the carriage in different positions.

35 10. In a tabulating mechanism for type-writing machines, the combination of a plurality of column-stop-controlling devices mounted on the carriage at fixed distances apart and adjustable laterally with respect to the direction of movement of the carriage to place them in or out of operative relation to stop-controlling means on the frame; a series of key-controlled stop devices on the frame, and means determining the operativeness of said key-controlled stop devices by the position of the laterally-adjustable stop-controlling devices on the carriage, substantially as described.

50 11. In a tabulating mechanism for type-writing machines, the combination of a series of stop-controlling lugs 4 mounted on the carriages at fixed distances apart and adjustable laterally with respect to the movement of the carriage; a series of key-controlled stop-levers 12 on the frame; graduated stop means 15' coöperating with the key-controlled stop-levers, and means actuated by the stop-controlling lugs on the carriage preventing or permitting the operation of the said stop-levers according to the lateral adjustment of said column-stops on the carriage, substantially as described.

60 12. In a tabulating mechanism for type-

writing machines, the combination of a series of column-stop-controlling devices 4 mounted on the carriage at fixed distances apart and adjustable laterally with respect to the movement of the carriage; a series of key-controlled stop-levers 12 on the frame; graduated stop means 15' with which such stop-levers coöperate, and an arresting device 10, 11, 12 interposed between the controlling devices 4 on the carriage and the stop-levers 12 on the frame and preventing the operation of said stop-levers in one position of adjustment of the respective controlling devices 4, substantially as described.

13. In a tabulating mechanism for type-writing machines, the combination of a series of equidistant laterally-adjustable stop-controlling tappet-lugs 4 on the carriage; a series of key-controlled stop-levers 12 on the frame, stop means with which such stop-levers coöperate, an arresting-lever 11 permitting or preventing the operation of the said stop-levers, and a lever device 10 engaged by the successive tappet-lugs 4 in one position of their adjustment so as to hold the arresting-lever 11 in fixed relation to the stop-levers 12, or release it therefrom, substantially as described.

14. In a tabulating mechanism for type-writing machines, the combination of a series of key-controlled stop-levers 12, graduated stop means 15' on the feed-drum with which said stop-levers coöperate; a release-lever 18, and a connection between the stop-lever 12 and release-lever 18 causing said release-lever to be actuated by the movement of either of the stop-levers, substantially as described.

15. The combination with the carriage, of a rotating member geared thereto, stop devices carried by said member peripherally and at fixed distances apart, each device comprising a series of graduated denominational stops, and key-controlled means coöperating with said denominational stops to arrest the carriage at different positions.

16. The combination with the carriage, of a rotating member geared thereto, stop devices carried by said member peripherally and at fixed distances asunder, each device comprising a series of fixed graduated denominational stops, and key-controlled means coöperating with said stop devices to arrest the carriage in different positions.

17. The combination with the carriage, of a rotating stop-carrier geared thereto, stop devices on said carrier, each comprising a series of graduated denominational stops, and key-controlled means engaging said denominational stops to arrest the carriage at different positions.
